UNITED STATES PATENT OFFICE.

CHARLES L. PALMER AND JOHN R. HOLLISTER, OF SLEEPY EYE, MINNESOTA.

WILD-PEA SEPARATOR.

1,368,746.

Specification of Letters Patent. Patented Feb. 15, 1921.

Application filed June 16, 1919. Serial No. 304,391.

To all whom it may concern:

Be it known that we, CHARLES L. PALMER and JOHN R. HOLLISTER, citizens of the United States, residents of Sleepy Eye, county of Brown, State of Minnesota, have invented certain new and useful Improvements in Wild-Pea Separators, of which the following is a specification.

The object of our invention is to provide a machine designed for separating wild peas from wheat and other grains in which advantage is taken of the difference in shape of the kernels of grain and the peas, the grain lying flat upon the supporting pans or plates and being shifted thereon through the movement of the plates while the peas loosened and separated from the grain by such movement, roll down the incline of the plates and thereby become separated from the grain which is discharged at the upper end of the plates.

A further object is to provide a machine in which the separating surfaces may be conveniently multiplied and the capacity of the machine thereby increased to any desired degree.

Other objects of the invention will appear from the following detailed description.

The invention consists generally in various constructions and combinations, all as hereinafter described and particularly pointed out in the claims.

In the accompanying drawings forming part of this specification.

Figure 1 is a vertical sectional view through a pea separating machine embodying our invention,

Fig. 2 is an end elevation of the same,

Fig. 3 is a plan view,

Fig. 4 is a detail sectional view of the ratchet mechanism by which the desired movement is imparted to the separating plates or pans.

Fig. 5 is a sectional view on the line 5—5 of Fig. 4.

Fig. 6 is a detail view of one of the eccentrics through which the desired movement is imparted to the hopper feed plate.

In the drawing, 2 represents the frame of the machine of any suitable size and construction. In the upper portion of this frame is a hopper 3 wherein the mixture of wild peas and grain is placed. This hopper is provided with the usual slide 4 for regulating the volume of feed from the hop-

per. Beneath the hopper is a feed plate 5 supported by links 6 and 7 from the frame of the machine and operating through rods 8 which extend to eccentrics 9 on a shaft 10 that is provided with a fly wheel 11 and is operated through a crank 12. The machine may of course be operated by power if preferred. So far this machine is of ordinary construction and we make no claim thereto, as any suitable means may be employed for delivering the mixture of grain and peas to the separating devices which we will now describe in detail.

13 represents a shoe, supported by links 14 which are pivoted at 15 to the frame of the machine at each end of the shoe. In this shoe a series of plates or pans 16, 16^a, 16^b and 16^c are mounted. The pan 16 is positioned to receive the mixture of grain and wild peas from the feed plate 5, said pan 75 being in parallel relation with the other pan beneath it and all of them inclined slightly to the horizontal, sufficiently to cause a round body, such as a wild pea, to start and roll by gravity on the upper surface of the 80 pan as soon as the pea becomes separated sufficiently from the grain kernels to permit of freedom of such movement. It will be understood that other spherical seeds besides wild pea can be separated from kernels 85 of grain in the manner herein described.

Spouts 17, 17^a and 17^b form inclined surfaces at the upper ends of the pans to receive the kernels of grain therefrom and direct them and the peas which may be mixed therewith from one pan to the pan next beneath, and thereby the separating surface may be increased to any desired extent by the simple multiplication of the pans and the connecting spouts between them. Each 90 spout is so arranged that the mixture of grain and wild peas delivered thereto from the upper end of the pan directly above will be discharged upon the middle portion of the pan next beneath, where a separation of 100 the grain and peas will take place, the peas that are loosened and separated from the kernels of grain rolling down over the pan while the grain kernels and some of the peas not separated at that time will flow upwardly and into the adjacent spout beneath for delivery to another pan. Comparatively light coiled springs 18 are connected with the shoe and with the frame of the machine and larger springs 19 are also connected 110

with the shoe and with the machine frame and operate against the tension of the springs 18, as indicated in Fig. 1.

To accomplish the desired result in machines of this kind, we have found it desirable to move the grain kernels upwardly on the separating pans through a quick jerk of the shoe and the mechanism for imparting this movement to the shoe we will now 10 describe in detail.

The shaft 10 has an eccentric 20 mounted thereon and a strap 21 has a fork connection 22 with the upper portion of the shoe eccentric with respect to the pivotal connections 15 of the links 14. The eccentric 20 is loose on the shaft, being encircled by the strap 21 and this eccentric is provided with a ratchet 23 at one end. A dog 24 is mounted on an arm 25 that is secured to 20 the shaft 10 and engages the teeth of the ratchet, being normally held in contact therewith by a spring 26. The revolution of the shaft 10 will, of course, impart a corresponding movement to the arm 25 and the dog 24 25 and the dog engaging the ratchet will revolve the eccentric on which the ratchet wheel is mounted. This movement will continue until the eccentric passes the dead center of revolution and at this point the power 30 of the spring 19 will be sufficient to move the eccentric faster than the dog and the arm 25 and the result will be a quick or abrupt movement of the shoe in a longitudinal and upward direction, the eccentric 35 slipping on the shaft and moving away from the actuating dog. During this quick upward stroke of the shoe the grain and peas will be agitated, the kernels of the grain moving toward the upper end of each pan 40 while the peas, separated and loosened from the grain kernels, will roll down over the pans and be discharged upon the spout 27 and into the box 28 at one end of the machine. The separating action on each pan 45 will be the same, the material passing from one pan to another until the bottom pan is reached, where the grain will be discharged over the upper end of the lower pan into a suitable receptacle, not shown, provided for 50 such purpose.

If necessary, the grain may be passed through the machine again, but generally one operation is sufficient to remove all or the greater part of the wild peas.

55 The pans may, of course, be made of any suitable length and the number increased according to the degree of separation required and the desired capacity of the machine.

60 The supporting links 14 extend from their point of attachment on the frame downwardly and forwardly when the shoe is at the limit of its backward movement. The ends of the links attached to the shoe de- 65 scribe the arc of a circle when the shoe

moves forward through the action of the large springs and imparts to the shoe a forward and upward motion. The forward motion is greater than the upward motion and a pitching motion is thereby imparted to the separating pans for causing the grain to become separated from the wild peas and advance up the pans, while the peas roll downwardly thereon. It is also to be noted that the pitch or inclination of the spouts 75 17, 17^a and 17^b is considerably greater than that of the separating pans and therefore there is no possibility of the grain being moved backwardly on these spouts through the gyrating action of the shoe. 80

We claim as our invention:

1. A machine of the class described comprising a frame, a gang of grain separating pans pivotally supported in said frame and means for delivering the grain to be separated upon the upper pan of the gang, each pan having a flat comparatively long separating surface whereon the material to be separated is delivered between the middle portion and the upper ends of the pans, 90 means for gradually imparting a smooth, initial, backward, non-feeding movement to said pans and a subsequent rapid pitching forward movement in a combined horizontal and vertical direction terminating abruptly 95 at the limit of the stroke of said operating means, the elongated substantially cylindrical seeds such as wheat being fed forwardly and upwardly by the pitching motion of said gang at the end of its forward stroke 100 while the spherical seeds separated from the elongated ones by the pitching motion of the gang will roll by gravity to the discharge end of the pans.

2. A machine of the class described comprising a frame, a gang of grain separating pans pivotally supported in said frame and means for delivering the grain to be separated upon the upper pan of the gang, said pans being arranged at a slight inclination 105 in the gang and the forward end of each pan projecting in advance of the corresponding end of the pans above, the upper ends of the pans discharging the elongated seeds and the lower ends discharging the 110 spherical seeds, means for imparting an initial backward movement to said pans, springs for imparting a rapid forward movement to said pans in a combined horizontal and vertical direction terminating in 115 an abrupt pitching action at the end of the stroke of said oscillating means, the elongated seeds being fed forwardly and upwardly by the pitching action of the pans when near the end of their stroke and discharging said seeds from the upper end of one pan upon the pan next beneath at a 120 point between the middle portion of the pan and the upper end thereof, the spherical seeds separated by said pitching action roll- 125 130

ing down the incline of said pans to the lower ends thereof.

3. A machine of the class described comprising a frame, a gang of grain separating pans, links pivotally connected with the lower portion of said gang and with the upper portion of said frame, said pans being arranged one above the other with the forward ends of the pans projecting in advance 10 of the corresponding ends of the pans above, said pans being arranged at a slight incline sufficient to direct spherical seeds downwardly by gravity but insufficient to cause downward movement of elongated seeds, 15 said pans having comparatively long separating surfaces on the upper portions of which the material to be separated is directed from the separating surface of the pan above, means for delivering a mixture of 20 elongated and spherical seeds to the upper pan of the gang, mechanism connected with said gang for imparting a continuous movement in one direction to said gang at a comparatively slow speed, and springs put under tension by such movement for projecting 25 said gang in the other direction with a combined horizontal and vertical movement, said projecting movement terminating abruptly with a pitching action at the end 30 of the stroke of said mechanism, whereby

the elongated kernels will be fed up the incline of said pans with a step by step movement and the spherical kernels dislodged by the pitching action will roll by gravity to the lower ends of the pans. 35

4. A machine of the class described comprising a frame, a gang of grain separating pans pivotally supported in said frame, means for delivering the grains to be separated upon the upper pans of the gang, said 40 pans being arranged at a slight inclination in the gang, and the forward end of each pan projecting in advance of the corresponding end of the pan above, the upper ends of the pans discharging the elongated 45 seeds and the lower ends discharging the spherical seeds, means for imparting an oscillating movement to said pans, and means for conducting material passing over the upper end of each pan on to a succeeding pan of the series, at a point approximately near the center of said pan. 50

In witness whereof, we have hereunto set our hands this 9th day of June, 1919.

CHARLES L. PALMER.
JOHN R. HOLLISTER.
